FOREIGN PATENT DOCUMENTS

GB	2282631 A	4/1995
WO	2008096339 A2	8/2008

Primary Examiner — Cynthia Ramirez*(74) Attorney, Agent, or Firm* — The Dobrusin Law Firm, P.C.; Daniel P. Aleksynas(57) **CLAIM**

The ornamental design for a painters wheeled caddy, as shown and described.

DESCRIPTION

FIG. 1 is a perspective view of a painters wheeled caddy showing my new design.

FIG. 2 is a left side elevation view thereof.

FIG. 3 is a right side elevation view thereof.

FIG. 4 is a rear view thereof.

FIG. 5 is a top plan view thereof.

FIG. 6 is a front view thereof; and,

FIG. 7 is an exploded perspective view thereof.

The broken line showing of a bucket is included for the purpose of illustrating environment and forms no part of the claimed design.
